(57) **CLAIM**

The ornamental design for a golf club travel case, as shown and described.

DESCRIPTION

FIG. 1 is a perspective view showing the front and left side of our new design with phantom lines (through out all the figures) indicating handles which form no part of the claimed design;

FIG. 2 is a left side elevation of FIG. 1;

FIG. 3 is a right side elevation of FIG. 1;

FIG. 4 is a front elevation of FIG. 1;

FIG. 5 is a rear elevation of FIG. 1;

FIG. 6 is a top plan of FIG. 1; and,

FIG. 7 is a bottom plan of FIG. 1.
